UNITED STATES PATENT OFFICE.

JOHN AINSWORTH RICE, OF SAN FRANCISCO, CALIFORNIA.

CENTRIFUGAL ORE-SEPARATOR.

1,344,519.

Specification of Letters Patent. Patented June 22, 1920.

Application filed June 25, 1919. Serial No. 306,562.

To all whom it may concern:

Be it known that I, JOHN A. RICE, a citizen of the United States, and a resident of San Francisco, in the county of San Francisco and State of California, have made certain new and useful Improvements in 5 Centrifugal Ore-Separators, of which the following is a specification.

This invention is an improved centrifugal 10 ore separator, especially adapted for separating materials differing in specific gravity, such as mineral particles from mill pulp, particles of minerals from flue dust, or bag house products, different minerals 15 constituting concentrates, liquids which may be caused to separate into liquids differing in specific gravity, and gases such as furnace gases from smelters, where it may be desirable to extract finely divided dust particles 20 from gas, or to separate two gases differing in specific gravity.

The object of my invention is to provide an improved machine of this character 25 which is simple in construction, is reliable and efficient in operation and which is automatically controlled.

Another object of the invention is to effect 30 improvements in the construction of the centrifugally acting separating element, whereby the pressure or centrifugal weight 35 of the heavier material is availed of to cause the lighter material or tailings to be discharged.

Another object of the invention is to combine 35 with the said separating element centrifugally acting means to automatically regulate the discharge of the heavier material.

Another object of the invention is to provide 40 means for automatically controlling the operation of the discharge regulating means and causing the same to control the discharge of the heavier material to a fine degree.

With the above and other objects in view 45 the invention consists in the construction, combination and arrangement of devices hereinafter described and claimed.

In the accompanying drawings:—

Figure 1 is a vertical central sectional 50 view of a separating machine especially adapted for use in treating material such as before specified and constructed in accordance with one embodiment of my invention.

Fig. 2 is a horizontal sectional view of the

same on a plane extending through the upper member of the separating element.

Fig. 3 is a detail vertical sectional view of the separating element, and showing one of the circuit breakers and associated members.

Fig. 3 $\frac{1}{2}$ is a similar view of the same, showing the other circuit breaker and associated members.

Fig. 4 is a diagrammatic vertical central 65 sectional view of another modified embodiment of my invention and which is especially adapted for use in separating gases, such as smelter smoke, which differ in specific gravity, and in separating flue dust and 70 finely divided particles such as smoke particles from said gases.

The frame 1 may be of the construction here shown or of any other suitable construction, and is provided at the bottom 75 with a hopper 2 which has an inclined bottom 3 and a discharge spout 4. Cross bars 5, near the upper end of the frame are provided with a vertical tubular bearing member 6, which is arranged centrally of the 80 frame, and lower cross bars 7 have a bearing member 8, which is also arranged centrally of the frame.

A vertical tubular shaft 9 has its upper end provided with a ball bearing 10, with 85 which the member 6 is equipped. Said tubular shaft has an annular flange 11 at a suitable distance from its lower end, and which bears on certain of the bearing balls of a ball bearing 12, with which the member 90 8 is equipped.

A separating element comprises a disk 13, a cover 14 over the disk and a ring 15 below the disk. The cover has a depending peripheral flange 16 and the ring has a peripheral wall 17 which is coincident with and below said flange. The diameter of the disk is less than that of the cover and ring, so that an annular pocket 18 is formed on the ring and between the same, the disk 100 and the cover. The inner edge of the ring is beveled on the upper side as at 19. The cover has a central opening 20, and is connected to the disk for rotation therewith by means of flights or ribs 21 which are tangent to a circle concentric with the disk and extend outwardly to within a short distance of the rim of the disk as shown in Fig. 2. The disk is secured by means of a hub member 22 to the tubular shaft 9, for rotation 105 110

with said shaft. Said hub member has a substantially truncated conical upper end which projects through the opening 20, as shown. The ring is supported by radial 5 arms 23, which project from a sleeve hub 24, which is on the lower end of the tubular shaft and is arranged for slight vertical movement, so that the ring may be slightly raised or lowered as required to regulate the 10 discharge of the heavier particles of the concentrates.

A vertical rod 25 extends through the tubular shaft and projects above and below the same. A nut 26 is screwed to the lower 15 end of said rod and bears under the sleeve hub. The upper end of said rod is swivelly connected as at 27 to the diametrically enlarged lower end 28 of a vertical screw 29, which is arranged and vertically movable in 20 the bearing member 6. The upper portion of the screw is unthreaded and is arranged for vertical movement in a bearing member 30, which is here shown as supported by cross bars 30^a at the upper end of the frame.

25 A gear nut 31 is threaded engaged with said screw and is mounted between ball bearings 32 which are arranged between the bearing members 30 and 6.

The tubular shaft 9 is provided with a 30 pulley 33 which is driven by a power belt 34 and hence said tubular shaft and the separating element which is carried thereby are rotated, when the machine is in operation. The material to be treated is fed to 35 the separating element through the opening 20 by a supply hopper 35. A supply chute 36 is here shown to supply material to said hopper.

The rod 25 has an annular groove 37 40 which is engaged by the arms 38 of a pair of oppositely inclined levers 39. Said levers are pivotally mounted as at 40 between pairs of lugs 41 on the flange 11 and have their outer portions screw-threaded and provided with centrifugally acting weights 42, 45 which are screwed and are adjustable thereon. The said weights and levers tend, in co-action with the rod 25 to raise the ring and to close its flange wall 17 against the lower 50 edge of the flange wall 16 of the cover.

At opposite sides of the tubular shaft are vertical shafts 43, 44, the lower ends of which are respectively stepped in bearings 45, 46, with which cross bars 47 of the frame 55 are here shown as provided. Said shafts are respectively provided with pulleys 48, 49, said pulleys having armatures 50, 51, respectively on their upper sides. The pulley 48 is connected to the tubular shaft by a belt 52, and the pulley 49 is connected to the tubular shaft by a crossed belt 53.

60 Electro-magnets 54, 55 are respectively associated with the pulleys 48, 49. Electro-magnet 54 has a tubular shaft 56, which is 65 mounted for rotation with relation to the

shaft 43, has its upper portion mounted in a bearing 57 and is provided with a pinion 58, which engages the gear nut 31. The electro-magnet 55 has a tubular shaft 59 which is mounted for relative rotation on 70 the shaft 44, and is also mounted in a bearing 60 and is provided at its upper end with a pinion 61 which also engages the gear nut 31.

The electro-magnet 54 is connected in 75 electric circuit with a battery 62 or other source of electric energy and with an adjustable contact 64 on one side of the separating element, by conductors 63. The electro-magnet 55 is connected in circuit with the battery 62 and with an adjustable contact 65 on the opposite side of the separating element by means of conductors 66. The electric-circuits are here illustrated diagrammatically. Normally each circuit is 80 85 open and hence the electro-magnets are normally deenergized. The said contacts are here shown as screws mounted in brackets 67 supported on and insulated from the separator. The contact 65 has an annular 90 flange 68 at its lower end.

I also provide pressure operated means to coat with the contacts to successively complete one circuit and open the other circuit, and which I will now describe. A cylinder 95 69 is arranged in a vertical opening in the cover of the separating element and is open at the upper end, the lower end of the cylinder being closed by a flexible diaphragm 70 which is stretched across said opening and secured at the periphery. A weight piston 71 is secured on the center of said diaphragm and has an upwardly extending rod 72, which has an arm 73 at the upper end adapted to come in contact with the 100 lower end of the contact screw 64 when the diaphragm and weight piston are moved upwardly.

A cylinder 73 is arranged in a vertical opening in the opposite side of the cover 110 of the separating element and is open at its upper end, the lower end of said cylinder being closed by a flexible diaphragm 74, which is stretched across said opening and secured at its periphery. A weight piston 115 75 is secured on the center of said diaphragm and has an upwardly extending rod 76, which rod has a laterally extending arm 77 at its upper end. Said arm is above the flange 68 of the contact screw 65.

120 Centrifugally acting levers 78, 79, are respectively provided to coöperate with the weight pistons 71, 75. Said levers are pivotally mounted on the cover of the separating element as at 80, 81. The lever 78 has an arm 82 at its lower end which engages in an opening in the rod of the piston 71. The lever 79 has a similar arm 83 which engages in an opening in the rod of the piston 75. Said levers are oppositely inclined and 130

are respectively provided near their upper ends with weights 84, 85.

The operation of my invention is as follows:—The material to be treated is fed by 5 the chute 36 and hopper 35 through the opening 20 into the revolving separating element and onto the central portion of the disk or table 13. The disk acts centrifugally to cause the material to move toward the periphery thereof, as will be understood, and 10 all the material, including the fluid part, passes over the periphery of the disk, where a partial separation takes place, according to the various degrees of specific gravity of 15 the material, the heaviest particles collecting on the ring or lower member of the separating element, in the pocket 18, and against the wall 16, 17, and owing to its superior specific gravity and consequent superior centrifugal weights, displacing the fluid and 20 the lighter particles and forcing the same centripetally toward the axis and causing the same to flow through the channel between the ring and the disk, to the discharge 25 at 19. The tailings discharge, after leaving the vicinity of said channel, flows over the beveled inner edge of the ring, where any remaining heavy particles will settle on said beveled surface and tend to gravitate into 30 the pocket 18, while the lighter particles and fluid, constituting the tailings, will discharge at 19 and fall into the hopper 2. The disk acts centrifugally to cause all material introduced at 20 to be carried to a place of 35 maximum centrifugal influence at 18, and causes the fluid to pass through the material collected at 18, separating the particles and permitting the heaviest particles to pass through the annular opening 86 formed between the flanges 16, 17, which constitute 40 the peripheral wall of the separating element.

The weights 42 having been appropriately adjusted, heavy concentrate accumulates in 45 the pocket and against the annular wall of the separating element and also by its pressure and centrifugal weights presses upwardly against the diaphragms 70, 74. When the pressure becomes sufficient to 50 cause the diaphragm 70 to cause the contact 72 to engage the contact 64, an electric circuit is completed through the electromagnet 54, said electromagnet is energized, and hence by 55 attracting the armature 50 which is carried by the pulley 48, said pulley, which is constantly revolved in one direction, coacts with the said electromagnet to form an electric clutch, said magnet is caused to revolve with said pulley, and hence the pinion 58 causes 60 the gear nut 31 to turn in the required direction to move the screw 29 and hence also the rod 25 downwardly, thus slightly lowering the ring or lower member 15 of the separating element, and correspondingly widening 65 and opening the annular discharge opening

86 and permitting a regulated discharge of the heavier concentrate.

Under the conditions described, the opening 86 will continue to widen until the pressure at 18 has been relieved by discharge of 70 concentrates, when the relieved pressure will cause a reverse movement of diaphragm 70 and a consequent breaking of electric circuit at 72—64, and opening 86 will cease widening and opening. 75

The machine will now operate with said opening 86 of constant size until the pressure decreases to a certain minimum. If it decreases to a certain minimum the diaphragm 74 will by the lowering of the piston 80 weight 75 cause an electric circuit, including the electro-magnet 55, to be closed by the contacts 65, 77, and since the pulley 49 revolves in the opposite direction to the pulley 48, the electro-magnet 55, by attracting the armature 51 will be caused to revolve with the said pulley 49, an electric clutch being formed by said electro-magnet and said pulley, and hence the pinion 61 and gear nut 31 will permit the centrifugally acting weights 42, and associated levers 39, to slightly raise the rod 25, thus correspondingly raising the ring 15 and hence decreasing the width of the discharge opening 86, 90 as will be understood. 95

Hence the discharge of the heaviest concentrate is automatically controlled by the centrifugal weight and consequent pressure of such concentrate and the effective area of the discharge opening of the centrifugally 100 acting separating element is varied according to the accumulation of the heavier concentrate in the peripheral portion thereof.

The weights 42 and levers 39 would not of themselves automatically control the discharge of the material to a sufficiently fine degree, but by the provision of the electric clutch mechanism and the pressure actuated circuit closing devices hereinbefore described to control the operation of the centrifugally 105 acting weights and levers I attain a complete automatic control of the discharge of concentrate, notwithstanding changes of speed in the revolution of the separating element, or variation or irregularities in the 115 feeding of the material to the machine or lack of homogeneity in the material being treated.

Within the scope of my invention any suitable means may be employed to relatively adjust the members of the separating element and thereby vary the effective area of the discharge opening thereof, and any suitable means may be employed to automatically control the operation of such adjusting means, and I would have it understood that I do not limit myself to the means here shown and described for these purposes. 120

In Fig. 4 of the drawings I show a modified form of my invention which is especially 130

adapted for separating solid particles from gases such as smelter smoke and the like and for the separation of two gases of different specific gravity.

5 A smoke pipe 87 leads from a furnace and has an upwardly directed elbow 88. The separating element comprises a truncated conical upper member 89, an inverted truncated conical lower member 90, and a 10 centrifugal disk or table 91. Said members 89, 90, are respectively provided at their smaller ends with cylindrical portions 92, 93. The cylindrical portion 93 fits loosely and is free to rotate in the upper end of the 15 elbow 88. The cylindrical portion 93 fits loosely and is free to rotate in the lower end of the elbow 94 of a pipe 95, which leads to a smelter stack. Hence the products of combustion pass through the separating element.

A vertical tubular shaft 96 passes through the center of the separating element and also through the center of the elbows and has its lower end stepped in a bearing 97. 25 Said shaft has a suitable driving pulley 98. A rod 99 is arranged in the upper portion of the tubular shaft and has radial arms 100 which are attached to the lower member of the separating element. Suitable 30 blades or wings 101 to impart circular motion to the gases are attached to the tubular shaft and are arranged in the said lower member. The upper member is connected by arms 102 to the tubular shaft for rotation therewith. The disk or table is attached at the center directly to the tubular shaft. Suitable blades or wings 103 to take up part of the energy and utilize the same are arranged in the upper member. The 35 lower member may be slightly raised or lowered by the rod 99, which is vertically movable in the tubular shaft, and an annular discharge opening 104 is formed between the upper and lower members. The 40 width of this opening may be varied by adjusting the lower member as will be understood. To automatically effect such adjustment, I provide a pair of centrifugally acting levers 105, which are pivotally 45 mounted as at 106 on opposite sides of the upper portion of the tubular shaft and the arms 107 of which are engaged in an annular groove 108 with which the rod is provided. Weights 109 are on said levers and 50 in practice suitable means is provided to permit of adjustment of said weights as may be required.

The mixed gases containing particles of solid material enter the lower member of 55 the separating element and caused to rotate therewith by means of the blades or wings 101, and are deflected to a region of maximum centrifugal action by the disk. The solid particles or a heavier gas, will collect

in the periphery of the separating element 60 and are discharged therefrom through the opening 104. Such discharge is automatically regulated by the centrifugally acting weights and levers and the vertically adjustable lower separating member. The cleaned 70 gases pass from the separating element into the pipe 95 and from there to the stack.

I claim:

1. In a machine for separating materials differing in specific gravity, a separating 75 element mounted for rotation and comprising an upper member having a central inlet opening, a lower ring-like member, a peripheral discharge opening being formed between said members, and a table between 80 the members, and of less diameter than the members, said table extending over the opening of the ring-like member and forming with said members an annular peripheral chamber.

2. In a machine for separating materials differing in specific gravity, a separating element comprising upper lower members having opposed peripheral flanges between which there is a discharge opening, 90 the upper member having a central inlet opening, and tangential ribs on its inner face, and the lower member being in the form of a ring, and a table between the members and of less diameter than the said 95 members, said table extending over the opening of the ring-like member and forming with said members a peripheral annular chamber.

3. In a machine for separating materials 100 differing in specific gravity, a separating element comprising upper and lower members having opposed peripheral flanges, the upper member having a central inlet opening and tangential ribs on its inner face and the lower member being in the form of a ring, a table secured to ribs of the upper member and of a diameter less than that of the said members, said table extending over the opening of the ring-like members and 110 forming with said members an annular peripheral chamber, and means for adjusting the upper and lower members relatively one to the other to form a discharge opening between their flanges.

4. In a machine for separating materials differing in specific gravity, a separating element mounted for rotation and comprising an upper member having a central inlet opening and a depending peripheral 120 flange, a lower ring-like member having an upwardly extending peripheral flange opposite the flange of the upper member, and a table between the said members and of less diameter than the said members, and 125 extending beyond the opening of the ring-like member, the members forming an annular chamber, adjacent the flanges, and

means for moving the lower member toward and from the upper member to form a discharge opening between their flanges.

5. In a machine for separating materials differing in specific gravity, a separating element mounted for rotation and comprising an upper member, a lower member, and a centrifugally acting table forming also a baffle, means to automatically adjust one of the first named members toward and from the other to form a peripheral opening for the discharge of heavier materials between them and to vary the effective area of said opening, and means, controlled by variations in the centrifugal weights of the material in the separating element, to control the operations of said adjusting means.

6. In a machine for separating materials differing in specific gravity, a separating element mounted for rotation and comprising an upper, intake member, a lower, tailing discharge member, and a centrifugally acting table, forming also a baffle, centrifugally acting means to automatically adjust one of the first named members toward and from the other to form a peripheral opening between them for the discharge of heavier materials, and means to control the operation of said adjusting means, said controlling means including an element movable in one direction by the centrifugal weights of materials in the peripheral portion of the separating element and centrifugally acting means to move said movable element in the reverse direction.

7. In a machine for separating materials differing in specific gravity, a separating element mounted for rotation and having an intake member, a tailings discharge member, a baffle member, and a peripheral opening for the discharge of heavier material, means to automatically vary the effective area of said opening, and controlling means for the last named means, said controlling means including an element movable in one direction by the centrifugal weights of materials in the peripheral portion of the separating element, and countervailing means to move the said movable element in the reverse direction.

8. In a machine for separating materials differing in specific gravity, a separating element mounted for rotation and having an intake member, a tailings discharge member, a baffle member, and a peripheral opening for the discharge of heavier materials, means to automatically vary the effective area of said opening, and controlling means for the last named means, said controlling means including a translating element, and a circuit breaker, said circuit breaker including an element movable in one direction by the centrifugal weights of material in the peripheral portion of the separating element, and countervailing means to move

said movable element in the reverse direction.

9. In a machine for separating materials differing in specific gravity, a rotary separating element, comprising an upper member, a lower ring-like member, and a table between the members and extending beyond the opening of the ring-like member, the members forming a peripheral chamber and a peripheral discharge opening, and one of them being movable toward and from the other, means for automatically adjusting the movable member, and means controlled by material in the chamber of the element for moving the movable member to vary the area of the discharge opening.

10. In a machine for separating materials differing in specific gravity, a rotary separating element comprising an upper member, a lower ring-like member movable toward and from the upper member, and a table between the members and extending beyond the opening of the ring-like member, the said members having between them a peripheral chamber and a peripheral discharge opening, centrifugal means for adjusting the lower movable member, and means controlled by the material in the said chamber for moving the lower member to vary the area of the discharge opening.

11. In a machine for separating materials differing in specific gravity, a separating element comprising an upper member, a lower movable ring-like member, and a table between the members and extending over the opening of the ring-like member, the members forming between them a peripheral chamber and a peripheral discharge opening, and means controlled by the material in the chamber of the separating element for moving the lower member to vary the area of the discharge opening.

12. In a machine for separating materials differing in specific gravity, a separating element comprising a plurality of members of which one is movable up and down, said element having a peripheral chamber, and a peripheral discharge opening, and means controlled by the material in the chamber of the element for moving the movable member to vary the area of the discharge opening.

13. In a machine for separating materials differing in specific gravity, a separating element comprising a plurality of members the lower one of which is movable up and down, said element having a peripheral chamber and a peripheral discharge opening, and electrically operated means controlled by the material in the chamber of the element for moving the movable member to vary the area of the discharge opening.

14. In a machine for separating materials differing in specific gravity, a separating element comprising a plurality of members, the

- lower one of which is movable up and down, said element having a peripheral chamber and a peripheral discharge opening, electrically operated means for moving the said 5 movable member to vary the area of the discharge opening, and a circuit closing and breaking means controlled by the material in the chamber of the separating element.
15. In a machine for separating materials 10 differing in specific gravity, a separating element comprising a plurality of members the lower one of which is movable up and down, the element having an annular peripheral chamber and a peripheral discharge

opening, the upper member having cylinders above the said chamber, the upper ends of which are open and the lower ends of which are closed by flexible diaphragms, a rod connected with the movable member of the element, electro-magnets, gearing between the electro magnets and the rod, electric circuits, contacts carried by the upper member of the element, pistons in the said cylinders and carrying contacts, and centrifugally operated levers engaging the contacts of the pistons. 15 20 25

JOHN AINSWORTH RICE.
